UNITED STATES PATENT OFFICE.

GUSTAV GOLDMAN, OF BALTIMORE, MARYLAND.

DESIGN FOR A COAT-PAD.

SPECIFICATION forming part of Design No. 32,556, dated April 17, 1900.

Application filed February 27, 1900. Serial No. 6,765. Term of patent 7 years.

To all whom it may concern:

Be it known that I, GUSTAV GOLDMAN, a citizen of the United States of America, and a resident of No. 2000 McCulloh street, city of 5 Baltimore, State of Maryland, have invented a certain new and original Design for a Coat-Pad, of which the following is a specification.

My new and original design relates to a coat-pad to be used in the manufacture of garments.

Figure 1 is a plan view of the coat-pad. Fig. 2 is an edge view of the pad.

As shown, my design for a coat-pad consists of a crescent-shaped pad having an oval-shaped portion attached at the center of its long side to the center of the inner arc of the crescent, the center of the crescent and of the oval portion being thick and of uniform thickness and of the same thickness at the point 10 of union and of gradually-decreasing thickness all around the disconnected edges.

The leading and material feature of my design consists of a crescent-shaped pad and an oval-shaped pad connected at the center of the inner arc of the crescent and the center 25 of the long side of the oval, the crescent-shaped pad and the oval-shaped pad being thick and of uniform thickness and of the same thickness at the point of union and of gradually-decreasing thickness all around the 30 disconnected edges.

Having described my invention, what I claim as new, and desire to secure by Letters Patent, is—

The design for a coat-pad as herein shown 35 and described.

Signed by me at Baltimore city, State of Maryland, this 16th day of February, 1900.

GUSTAV GOLDMAN.
